Design U.S. Appl. No. 29/624,451, filed Nov. 1, 2017 in the name of Newtl.

Primary Examiner — Darlington Ly(74) *Attorney, Agent, or Firm* — Carter, DeLuca & Farrell LLP**CLAIM**

The ornamental design for a handrail and a roof panel of a bus, as shown and described.

DESCRIPTION

FIG. 1 is a top and right side perspective view of a handrail and a roof panel of a bus embodying my new design; FIG. 2 is a front elevation view thereof;

FIG. 3 is a left side elevation view thereof; and,

FIG. 4 is a right side elevation view thereof.

The broken lines depict the environment of the handrail and a roof panel of a bus that form no part of the claimed design.
